UNITED STATES PATENT OFFICE.

HENRY E. BRANDT, OF STILLWATER, MINNESOTA.

SPRAYER.

1,295,420.

Specification of Letters Patent. Patented Feb. 25, 1919.

Application filed September 3, 1918. Serial No. 252,488.

To all whom it may concern:

Be it known that I, HENRY E. BRANDT, a citizen of the United States, residing at Stillwater, in the county of Washington and 5 State of Minnesota, have invented certain new and useful Improvements in Sprayers; and I do hereby declare the following to be a full, clear, and exact description of the invention, such as will enable others skilled 10 in the art to which it appertains to make and use the same.

My present invention relates particularly to spraying devices wherein a tank for containing the liquid to be sprayed is equipped 15 with an air pump detachably applied thereto, and arranged to produce air pressure in the said tank. The invention is directed to improved means for interlocking the several elements of the pump to the tank, and generally stated, consists of the novel devices 20 and combinations of devices hereinafter described and defined in the claims.

The invention is illustrated in the accompanying drawings wherein like characters 25 indicate like parts throughout the several views. Referring to the drawings,

Fig. 1 is a plan view showing the tank equipped with my invention;

Fig. 2 is a side elevation showing the 30 upper portion only of the tank and its pump mechanism;

Fig. 3 is a horizontal section taken on the line 3—3 of Fig. 2 but with certain parts broken away and illustrating the construction of elements located below the said section line;

Fig. 4 is a vertical section on the line 4—4 of Fig. 3; and

Fig. 5 is a section taken approximately 40 on the same line as Fig. 4, but with some parts removed.

The tank is indicated by the numeral 6 and this tank, at the central portion of its upper side plate, has a rigidly secured internally threaded sleeve 7 for detachably 45 supporting the pump mechanism.

The pump which is of the reciprocating cylinder and piston type, is adapted to be operated by hand and comprises a cylinder 50 8 and a piston 9, the rod of which is shown in the drawings, but the piston head of which is not illustrated, since it may be of the usual or any suitable construction. To the upper end of the piston rod 9 is a rigidly 55 secured suitable hand piece 10, the lower end of the stem portion of which is provided

with outstanding diametrically opposite lock lugs 11.

A cylinder cap rim 12 is rigidly secured to the upper end of the pump cylinder 8 and 60 has internal screw threads for coöperation with the threads of the sleeve 7 to detachably hold the pump cylinder in working position with the tank. A pliable gasket 13 is countersunk into the under surface of the 65 outstanding flange of the rim 12 and is seated on the upper edge of the sleeve 7.

A cylinder cap 14 is detachably seated on the innermost portion of the rim 12 and is provided with outstanding lock lugs 15, as 70 shown, three in number. In the horizontal plane of these lugs 15 the rim 12 is formed with an internal lock channel 16 having, at circumferentially spaced points, stop lugs 75 or shoulders 17. Midway between the stop shoulders 17, the uppermost horizontal flange of the rim 12 is formed with lug entrance notches 18, through which the lock lugs 12, when turned into alinement therewith, may be moved either into or from the 80 said channels 16.

The cap 14 is also shown as provided with depending centering lugs 19 that engage with the interior of the rim 12 to center said cap, in respect to said rim. 85

The piston rod 9 is arranged to reciprocate freely through an axial passage in the cap 14 and the said cap is formed with an internal lug channel 20 into which the lock lugs 11 are adapted to be turned. The 90 uppermost inturned flange of the cap 14 is provided with diametrically opposite lug entrance notches 21 through which the lugs 11, when turned into alinement therewith, may be passed to and from alinement with 95 the said channel 20. Midway between the entrance notches 21 and within the channel 20, the cap 14 is provided with stop lugs or shoulders 22.

The important relation of the parts above 100 described will be made clear by the following description of the operation, or use thereof.

When the rim 12 is applied to the sleeve 7, and the cap 14 is turned so that its lock 105 lugs 15 are within the lock channel 16 (see particularly Figs. 3 and 5) which illustrate both a downward and inward camming action between the lugs 15 and the upper and outer walls of said channel. 110

When the tank has been properly charged, the piston will be pushed downward to its

limit, while the lugs 11 are turned into alignment with the notches 21, and thence, the lugs 11 are turned into the channel 20, thereby locking the piston down so that it ⁵ can not be forced upward by the re-action of the compressed air in the tank.

The manner of releasing the piston for use is obvious. Frequently it is desirable to remove the entire pump piston from the

- 10 pump cylinder without removing the cylinder from the tank. To accomplish this result, the hand piece 12 is gripped in one hand and the piston is rotated in a clock-wise direction, in respect to Figs. 1 and 3, until the
- 15 lugs 11 are moved past the coöperating entrance notches 21 and into engagement with the shoulders 22, and then, by constant rotation in the said direction, the cylinder cap 14 may be rotated until its lugs 15 are alined with notches 18 and then the said cylinder cap may be lifted from position by pulling upward on the hand piece 10, and will come away with the piston. If, however, instead of pulling upward on the cap when its lugs
- 20 15 aline with the notches 18, rotation is still further continued, lugs 15 would be moved in a clockwise direction past notches 18 and into engagement with stop shoulders 17, and then by continuing or forcing the rotation in
- 25 the said direction, the cap rim 12 can be unscrewed from the sleeve 7, and hence, removed with the pump piston and cap from the cylinder.

When the cylinder and cap are to be again secured in working position in respect to the tank, the rim 12 may be screwed into the sleeve 7, as far as it will go readily, by engaging the same with the hands, or it may be thus screwed into position simply by manipulation of the hand piece 10. By reference to Fig. 3 it will be noted that with the parts as they are positioned, if, by manipulation of the hand piece 10, the parts are rotated in anti-clockwise direction, lugs 11 will bear against shoulders 22 and lugs 15 will bear against shoulders 17, so that the said hand piece then becomes a power device for tightly screwing the rim 12 into the sleeve 7.

The above described lug and groove connections between the piston rod and cylin-

der cap, in the one instance, and between the cylinder cap and the cap rim in the other instance, form a species of bayonet joints in which the lugs are removed when in intermediate positions in which there is an interlocking and stopping action when the lugs are rotated in either direction from such intermediate positions, and then unlock the said parts so that the several parts may be released or removed, either individually, or ⁶⁰ collectively. This arrangement is thought to be broadly new.

What I claim is:

1. The combination with a tank and a pump comprising a cylinder and a piston, of a cap rim secured to said cylinder and connectible to and disconnectible from said tank by rotation, a cylinder cap connected to said rim by an interlocking bayonet joint, and the rod of said piston being detachably connectible to said cap by a bayonet joint, said bayonet joints limiting the rotary movement of the connected parts, the one in respect to the other.

2. The combination with a tank having a threaded sleeve, a pump cylinder, a pump piston, a cylinder cap, a cap rim secured to said cylinder and having threaded engagement with said sleeve, said rim having an internal lock channel with lug entrance notches and with stop shoulders intermediate of said entrance notches, said cylinder cap having lugs insertible into said lock channel through said lug entrance notches and engageable with said stop shoulders, said cap also having an internal lock channel with lug entrance notches and with stop shoulders intermediate of the lock entrance notches thereof, the stem of said piston having a hand piece and provided with lock lugs that are insertible into the lock channel of said cap through the entrance notches thereof and are rotatable into engagement with the stop shoulders of said cap.

In testimony whereof I affix my signature in presence of two witnesses.

HENRY E. BRANDT.
